UNITED STATES PATENT OFFICE.

JAMES E. PATE, OF KIPLING, LOUISIANA.

BRACKET FOR RADIUS RODS.

Application filed September 5, 1923. Serial No. 661,051.

This invention relates to a bracket for a radius rod which is adapted to be supported or connected at its forward or free ends to the axle of an automobile and being provided with means at the converging ends thereof for securely holding the rear end of the radius rod in position upon the car.

Another important object of the invention is to provide a bracket for a radius rod which is of such a construction as to provide a socket for receiving and supporting the ball formed on the rear end of the radius rod and which will furthermore prevent the radius rod from accidentally becoming disengaged from its supported position when the vehicle is traveling over a rough road.

A still further object of the invention is to provide a bracket for a radius rod of the above mentioned character, which will hold the rear end or portion of the radius rod in a secure position upon the vehicle and which will furthermore be of such a construction as to enable the same to be readily disengaged when it is desired to remove the radius rod.

A further object of the invention is to provide a bracket for a radius rod of the above mentioned character, which is simple in construction, inexpensive, strong, durable and further well adapted for the purposes for which it is designated.

Other objects and advantages of this invention will become apparent during the course of the following description.

In the accompanying drawings forming a part of this specification and in which like numerals designate like parts throughout the same:—

Figure 1 is a side elevation of my bracket showing the same in position upon a radius rod, and secured to a portion of the vehicle.

Figure 2 is a bottom plan view thereof.

Figure 3 is a sectional view taken on line 3—3 of Fig. 2, and

Figure 4 is a top plan view of my bracket.

In the drawings wherein for the purpose of illustration is shown the preferred embodiment of my invention, the numeral 1 designates generally the radius rod which is adapted to be associated with motor vehicles preferably of the Ford type and which acts in the capacity of a brace for the front axle. This radius rod 1 comprises or consists of the converging arms 2 and 3 respectively and are connected at their rear ends and terminate in a ball 4. The free ends of the

arms 2 and 3 are adapted to be connected to the front axle A in the usual manner and as this feature forms no important part of the present invention it is not thought necessary to further go into detail as to the manner in which the free ends of the arms of the radius rod 1 are secured to the axle.

For the purpose of holding the rear end of the radius rod in position upon the motor vehicle, I provide the bracket or cap designated generally by the numeral 5. This bracket 5 may be made of any suitable metallic material and comprises the body portion 6 and from which extends the lateral extensions 7 and 8 respectively. The purpose of these extensions 7 and 8 will be hereinafter more fully described. The body portion 6 of the bracket 5 is furthermore provided with a cutout portion or cavity which is designated by the numeral 9 in the drawings and is provided in the upper face thereof for the purpose of providing a socket or sleeve for the ball 4 of the radius rod 1 when the bracket is in position on the vehicle.

The forward portion 6 of the bracket 5 is provided with an extension which terminates into a hook 10. The hook 10 being formed approximately at a point directly forward of the cavity formed in the top of the body portion 6 of the bracket 5 and said hook is sufficiently narrow to provide for slight lateral and vertical play between the same and the arms 2 and 3. This socket 12 is of the usual construction formed on the automobiles of the Ford type and is for the purpose of receiving the ball 4 formed on the rear end of the radius rod. It is to be further understood that the socket 12 is provided with laterally extending portions to cooperate with the lateral extensions 7 and 8 in supporting the car or bracket 5 on the socket 12. Suitable bolt 13 being used for securing the cap or bracket 5 to the socket 12 and crank case B as clearly shown in Figures 1 and 2 of the drawing.

With the parts arranged as shown in Fig. 1 of the drawings, it will be seen that the ball 4 formed at the rear end of the radius rod 1 will be seated in the cavity 9 provided in the body portion 6 of the bracket 5 and the hook portion 10 formed at the forward end of the body portion of the bracket will extend between the angle formed by the converging ends of the arms and which will further enable the radius rod to be properly

supported in position upon the vehicle and will prevent the possibility of the radius rod from becoming accidentally disengaged from its supported position when the vehicle 5 is in operation.

Heretofore it has been found necessary to provide many parts for supporting the radius rod's rear end and furthermore considerable wear has taken place which has resulted in the necessity of causing considerable expense in replacing the worn parts. By providing a bracket of the above mentioned character the simplicity of the same 10 enables it to be readily and quickly placed in position upon the vehicle and will furthermore prevent the possibility of the rear end of the radius rod from moving around in the socket whereby wear on the socket is prevented. The hook 10 is sufficiently narrow to provide for slight vertical and lateral play of the arms 2 and 3.

From the foregoing description of the construction of my improved apparatus, it will be seen that I have provided a simple 15 and efficient means for carrying out the objects of the invention and while I have particularly described the elements best adapted to perform the functions set forth, it is obvious that various changes in form, proportion and in the minor details of construction may be resorted to, without departing from the spirit or sacrificing any of the principles of the invention.

What I claim as new and desire to secure 20 by Letters Patent is:—

1. As an article of manufacture, a radius rod supporting member including a ball socket with an outstanding and upturned supporting hook thereon.

2. As an article of manufacture, a radius rod supporting member including a cap portion having a socket opening therein, and a laterally extending hook outstanding from

said cap and rigid therewith, said hook having the free end thereof upturned toward the 45 entrance of said socket opening.

3. As an article of manufacture, an attaching cap for ball and socket constructions providing a head having a depression opening therein from a side thereof, and 50 an outstanding supporting substantially J-shaped hook connected to said head below the entrance of the socket opening therein, said hook being upturned at its free end in the direction of the entrance of said socket 55 opening.

4. In a device of the class described, a radius rod comprising a pair of converging arms terminating at their converging ends in a slight extension, a ball formed integral 60 with said extension, a two-part bracket each part comprising a body portion having hemispherical complementary sockets formed centrally to receive said ball therein, said sockets each having communication with a 65 forwardly extending groove, said groove being adapted for registration to receive the extension of the radius rod therethrough, laterally projecting and aligning lugs 70 formed on the parts of said bracket, means 75 extending through said lugs for securing the parts of the bracket together, and a hook member formed integral with and projecting forwardly from the lower part of said bracket to project into the angle formed at the converging ends of the arms of said radius rod, said hook being shaped to project slightly above the plane of the radius rod at the junction of the arms thereof to prevent undue vertical movement and being 80 of a width to prevent undue lateral movement of said rod, as and for the purposes described.

In testimony whereof I affix my signature.

JAMES E. PATE.
